UNITED STATES PATENT OFFICE.

ERNEST BOCCINO AND MATTEO DE CESARE, OF NEWARK, NEW JERSEY, AND ALEX BERNHEIMER, OF NEW YORK, N. Y.

DESIGN FOR A COMBINED TOY CLOCK AND WINDMILL.

Application filed January 18, 1926. Serial No. 16,158. Term of patent 3½ years.

To all whom it may concern:

Be it known that we, ERNEST BOCCINO, MATTEO DE CESARE, citizens of the United States, residing at Newark, in the county of Essex and State of New Jersey, and ALEX BERNHEIMER, a citizen of the United States, residing at New York, in the county of New York and State of New York, have invented a new, original, and ornamental Design for a Combined Toy Clock and Windmill, of which the following is a specification, reference being had to the accompanying drawing, forming part thereof.

Figure 1 is a front elevational view of the windmill side of the device.

Figure 2 is a side view of the same.

Figure 3 is a rear elevational view of the device.

We claim:

The ornamental design for a combined toy clock and windmill as shown.

ERNEST BOCCINO.
MATTEO DE CESARE.
ALEX BERNHEIMER.
